UNITED STATES PATENT OFFICE.

EUGENE W. CALDWELL, OF NEW YORK, N. Y.

ELECTRIC-CURRENT INTERRUPTER.

SPECIFICATION forming part of Letters Patent No. 677,498, dated July 2, 1901.

Application filed May 4, 1899. Serial No. 715,557. (No model.)

To all whom it may concern:

Be it known that I, EUGENE W. CALDWELL, a citizen of the United States, and a resident of the city of New York, in the borough of Manhattan, county of New York, and State of New York, have invented a certain new and useful Improvement in Apparatus for Interrupting Electric Currents, of which the following is a specification, reference being had 10 to the drawings accompanying and forming a part of the same.

The present invention relates to a new apparatus for interrupting, especially at high rate of frequency, an electric current or circuit.

The invention as herein illustrated and described is applicable to an interrupter for use in connection with an induction-coil, especially such a coil as is used for X-ray work; 20 but it is to be understood that this interrupter may be used with other apparatus requiring an electric-current interrupter.

In descriptive terms the invention consists of an electric conductor, a portion or section 25 of which is composed of a fluid, a part of which is so confined that as the current passes it will be evaporated or rendered gaseous, and thereby the circuit will be broken.

Referring to the drawings, Figure 1 illustrates one form of apparatus for practicing the invention. Fig. 2 is a cross-section on line *a a*. Fig. 3 is a modified form of the apparatus.

Referring to the views in detail, A represents a vessel of any proper material and size 35 and form of construction.

B represents a diaphragm or separating member integral with the walls of the main vessel or disconnectedly arranged relatively 40 to the same, which diaphragm is pierced by an open passage C.

D represents circuit-terminal plates or electrodes supported by any suitable means in position relatively to the diaphragm practically as shown in the figures. These plates are of sufficient size to effect full electrical communication with the fluid E contained in the receptacle A, which fluid is preferably acidulated water. Other terminals and other 45 fluids may be used. These terminals are connected to the wires F F, which for illustra-

tion form the primary G of the induction-coil H.

The action of the apparatus is as follows: Current passing through the fluid connecting 55 the terminals so heats the part of the fluid-conductor confined in the passage through the diaphragm as to cause such confined fluid to be vaporized or become gaseous or to expand in the form of bubbles, which will 60 interrupt the passage of the current, (or the most of the current, if not all,) whereupon the gas or bubble will tend to move from the confining-passage, and then the pressure of the fluid in the vessel will act to refill the 65 passage, the current will be remade, another bubble formed, and so on. This operation will go on with high and manageable frequency of current interruption and with sustained regularity, so that (as is found after 70 many and careful experiments) a high frequency and certain efficiency are secured for the purpose of interrupting an electric current or circuit. Such apparatus used to operate an induction-coil, especially for the purpose of X-ray work, is found to effect greater 75 steadiness as to the work of the secondary coil than that of any electric interrupter known to me.

Referring to Fig. 3, in lieu of the diaphragm 80 of Fig. 1 I use a tube I, which is perforated at J or any other place as requirements may demand, which tube contains the terminal K, and another terminal K is contained in the outer vessel, the solution or fluid being the 85 same as before.

In the last-mentioned case the tube constitutes a convenient member to be easily removed, so that tubes having passages of different sizes may be readily utilized to effect 90 various rates of interruption. In the case of Fig. 1 the passage there shown may be modified as to size, as by the removal therefrom of the small tube or passage-closing tube L.

The frequency of interruption can be varied 95 in different ways. The size of the passage in the partition between the terminals may be increased or diminished. The passage may be of a fixed size and the terminals be brought closer together or placed farther 100 apart than is shown. The electrical conductivity of the fluid can be varied and the grav-

ity action of the fluid can be utilized for the same purpose.

Generally speaking, it is found that after the apparatus has been in use for a short time the fluid in the containing vessel will be brought to a temperature that will remain practically stationary, whereupon the frequency of interruption becomes uniform, although it should be understood that the apparatus works instantly at ordinary temperature upon the closing of the circuit, though with an increasing rate of interruption as the fluid rises in temperature.

I am aware that electric-circuit interrupters involving electrolytic action have heretofore been suggested. In the present case the essential interrupting action is that of heating a confined part of a body of conducting fluid by the passage of the electric current through such part, so that it is formed into steam or gas.

What is claimed as new is—

1. An electric interrupter comprising two electrodes, a conducting fluid between them, a perforated insulating separating medium between the electrodes forming a reduced section of the fluid between the electrodes and means for subjecting said reduced portion of the fluid to pressure.

2. An electric interrupter comprising two electrodes, a conducting liquid between them, a perforated wall of insulating material between said electrodes, forming a reduced section of said conducting liquid, said reduced section of said liquid being subjected to the pressure of the superposed liquid.

3. An electric interrupter comprising two electrodes, a conducting liquid between them, and a perforated insulating separating medium between the electrodes maintaining a uniform open relation of the liquid to the electrodes.

4. An electric interrupter comprising two circuit-terminals, a liquid conductor between them and in continuous open relation to them, a perforated wall of insulating material between them, and means for adjusting the size of the opening in the wall.

5. An electric interrupter comprising the vessel A, the outer electrode K, the tube I and contained electrode K, the said tube having an open passage J through the same, for the purposes set forth.

EUGENE W. CALDWELL.
